New York, N. Y., a corporation of New York

Application November 29, 1933, Serial No. 700,246
In France December 15, 1932

7 Claims. (Cl. 179—16)

This invention relates to signaling systems and more particularly to circuit arrangements for transmitting and receiving direct current impulses over lines, the sections of which are inductively connected by repeating coils or transformers.

In telephone systems in which connections are established between widely separated points over interconnecting trunk circuits, it is necessary in order to obtain efficient transmission to employ in the trunk circuits repeaters involving repeating coils. If the connections over the trunk circuits are to be established by means of machine switching apparatus it then becomes necessary to repeat dialing impulses around or through the repeater connections between the sections of the established circuit.

It is well known that if an impulse of direct current is transmitted through the primary winding of a repeating coil that one impulse will result in the secondary winding of the coil on the closure of the direct current path through the primary winding and that a second impulse will result in the secondary winding on the opening of a direct current path through the primary winding. This would obviously result in the reception in the circuit associated with the secondary winding of twice the number of impulses transmitted.

In accordance with the present invention in which direct current impulses are dialed into a path through the primary winding of a repeating coil, the receiving equipment associated with the secondary winding is arranged to respond only to the impulses resulting in the secondary winding due to the breaks or openings of the circuit through the primary winding. This is accomplished by the provision of a rectifier connected in series with the impulse responsive relay which is bridged across the secondary winding of the repeating coil, the rectifier being so poled that current can flow therethrough and through the winding of the responsive relay only when the circuit through the primary winding of the coil is opened by the opening of the impulse transmitting device contacts, for example, the impulse dial contacts.

In accordance with a further feature of the invention, provision is made for correcting the impulses received by the responsive relay so that should they be too short to properly operate receiving equipment such as a selector switch or impulse repeater, they may be corrected to a predetermined duration which is independent of the duration of the impulses received. This is

accomplished by providing a secondary impulse responsive relay which is polarized or biased by a rectifying device connected in parallel with the windings thereof and which is responsive to the operation of the primary impulse responsive relay. The secondary relay in turn may operate a quick-acting impulse repeating relay if it is desired to repeat the received impulses over a further section of the trunk or may directly operate the stepping magnet of a selector switch.

In accordance with a further feature of the invention long signaling impulses of closely spaced direct current impulses or of alternating current of a suitable frequency to which the direct current impulse responsive device will continuously respond may be transmitted. These impulses may be employed as desired to operate suitable signaling apparatus at the distant or at intermediate points in the trunk circuit.

The invention will be more clearly understood from the following description of one embodiment thereof shown in the accompanying drawing.

At the extreme left of the drawing is shown an impulse transmitting station. In the central portion of the drawing a repeating station is shown and at the extreme right of the drawing a receiving station is shown. The trunk conductors between the transmitting station and the repeating station are connected by repeating coils 100 and 101 and the trunk conductors between the repeating station and receiving station are connected by repeating coils 102 and 103. It will, of course, be obvious that additional repeating stations, similar to that disclosed, could be inserted with the required repeating coils between the repeating station disclosed and the receiving station.

When the dial 105 at the transmitting station is moved from normal to transmit impulses to set a selector switch at the distant receiving station, ground is connected over the off-normal contacts of the dial to the back contact of relay 106, but relay 106 being operated this ground is ineffective at this time. When, however, the dial returns to normal the circuit of relay 106 is interrupted intermittently by the impulse contacts of the dial and upon each interruption the circuit from the off-normal ground of the dial is extended over the back contact of relay 106, through the winding of relay 107 and the left winding of relay 108 to battery. Relay 108 responds to the impulse and renders itself slow to release by short phasing its right winding so that it remains operated throughout the train of im-

pulses and connects condenser 109 and resistance 110 in shunt of the primary winding of repeating coil 100 to prevent high currents and high tensions in the trunk.

- 5 Relay 107 operates and releases at the beginning and end of each impulse, connecting and disconnecting battery and ground to and from the primary winding of repeating coil 100 through the normal contacts of key 111 so that 10 short, direct current impulses are transmitted through the secondary winding of repeating coil 100 and the primary winding of repeating coil 101 at each make and break of the current in the primary winding of repeating coil 100. It is 15 to be understood that the primary winding of repeating coil 100 should be practically saturated at each impulse. The two impulses thus transmitted for each dialed impulse are opposite in direction and the break impulse is of greater 20 strength than the make impulse. At the end of the train of impulses relay 108 releases.

At the repeating station each impulse is induced into the secondary winding of repeating coil 101 and passes through the winding of primary impulse responsive relay 112 in series with the rectifier 113 which is poled so as to pass the impulses resulting from the breaks of the dial contacts and to reduce the strength of or bar the impulses resulting from the makes of the dial contacts. Relay 112 upon each operation closes its contacts just sufficiently to operate the secondary impulse responsive relay 114, relay 114 having a small number of turns to render it quick to operate. To limit the current flowing 25 through the winding of relay 114 to a desired value, resistances 115 may be placed in series therewith. Relay 114 is given a releasing time equal to the length of impulse desired by the rectifier 116 which is connected in parallel with its winding. Each short impulse received over the trunk by the relay 112 therefore produces an impulse corrected to a predetermined length in the receiving equipment controlled by the contacts of relay 114.

45 The difference between successive impulses received by relay 112 is very small and the difference in the operation of relays 112 and 114 is also very small during a train of impulses. The time between successive impulses is therefore very little distorted even with many repetitions of impulses.

At its contacts relay 114 closes a series circuit through the windings of relays 117 and 118. Relay 118 upon operating renders itself slow to release by short circuiting its left winding and connects an impulse shaping shunt comprising condenser 119 and resistance 120 around the primary winding of repeating coil 102. Slow-to-release relay 121 being normally operated, battery and ground are connected over its alternate contacts and the front contacts of relay 117 to the primary winding of repeating coil 102 during each operation of relay 114, and, consequently, make and break direct current impulses are transmitted through the secondary winding of repeating coil 102 and the windings of repeating coil 103 to the equipment at the receiving station.

70 At the receiving station each impulse passes through the winding of primary impulse responsive relay 122 in series with the rectifier 123 which is so poled as to pass the break impulses and to reduce the strength of or bar the make impulses.

75 Relay 122 upon each operation closes its contacts

just sufficiently to operate the secondary impulse responsive relay 124, relay 124 having a small number of turns to render it quick to operate. To limit the current flowing through the winding of relay 124 to a desired value, resistances 125 may be placed in series therewith. Relay 124 is given a releasing time equal to the length of impulse desired by the rectifier 126 which is connected in parallel with its winding. Each short impulse received by relay 122 therefore produces an impulse corrected to a predetermined length in the receiving equipment controlled by the contacts of relay 124. At the front contact of relay 124 upon each energization thereof, a circuit is established for stepping magnet 127 of a selector switch or other apparatus which it is desired to operate in response to dialed impulses.

To transmit a signal from the transmitting station to the receiving station for any purpose as, for example, to attract the attention of an operator or attendant, the key 111 is operated. The operation of this key closes the circuit of relays 107 and 108 which operate, relay 108 establishing the impulse shaping circuit including condenser 109 and resistance 110 in shunt of the primary winding of repeating coil 100 as previously described, but relay 107 performs no useful function at this time since with key 111 operated it cannot connect battery and ground to the primary winding of repeating coil 100. At 30 its inner alternate contacts key 111 connects the source 128 of alternating current to the primary winding of coil 100. This source of current may be of 32-cycle frequency which may be obtained from a 16-cycle ringing machine by a common transformer and two rectifiers or alternatively a 50-cycle supply of alternating current, if available, may be used.

Current from the source 128 operates relay 112 steadily which, in turn, holds relays 114, 117 and 118 operated. With relay 117 operated, slow-to-release relay 121 releases, disconnecting battery and ground from the primary winding of repeating coil 102 and connecting the source 129 of alternating current thereto. This source may be similar to the source 128. In response to the connection of source of current 129 relay 122 is steadily operated and, in turn, maintains relay 124 operated. Relay 124 being steadily operated opens the circuit of slow-to-release relay 130 for a time sufficient to permit the release of this relay, which at its back contact closes the circuit of a suitable signaling device such as the lamp 131.

Since battery is connected to the primary winding of repeating coils 100 and 102 for a minimum time long enough to reach at its disconnection a current value which is near the maximum, the strength of the impulse is not influenced much by variations in the potential of the battery and by the length of the time the contacts of relays 107 and 117 are closed. Also since relays 114 and 124 are nearly saturated their operating and releasing times do not depend much on the battery voltage. The system does not require any special source of current, such as 128 or 129, as when long signals are to be transmitted the regular battery may be connected in place of the sources 128 and 129 through the operation of key 111 and release of relay 121 and closely spaced impulses transmitted therefrom.

From the foregoing it will appear that the system is very simple, does not require any special source of current or special relays having deli- 15

cate adjustment and requiring abnormal maintenance and that dialing may be effective at dialing speeds between 8 and 14 impulses or more per second.

5 Instead of using serially connected rectifiers in the circuits of relays 112 and 122 these relays may be biased by a 4-volt accumulator or these relays may be replaced by polarized relays without rectifiers or by neon tubes which are biased by polarizing batteries and become conducting when subjected to the additional potential of the incoming impulses and when conducting operate the secondary impulse responsive relays. To make relays 112 and 122 responsive to weaker impulses 10 they may be provided with permalloy cores or may be initially polarized to reduce the effect of inverse or make impulses and to increase the effect of the desired or break impulses. Relays 114 and 124 may also be made slow-to-release by 15 other means than the parallelly connected rectifiers 116 and 126 as by providing them with auxiliary short-circuiting windings such as shown on relays 108 and 118.

What is claimed is:

25 1. In a signaling system, a transmitting station, a receiving station, a line extending between said stations and divided into sections, a repeating coil for uniting said sections, means at said transmitting station for transmitting impulses of direct current to the primary winding of said repeating coil, and an impulse responsive relay connected in series with a rectifier in circuit with the secondary winding of said repeating coil at said receiving station, said relay being so polarized by said rectifier as to be responsive only to the break impulses set up by said transmitting means.

30 2. In a signaling system, a transmitting station, a receiving station, a line extending between said stations and divided into sections, a repeating coil for uniting said sections, means at said transmitting station for transmitting impulses of direct current to the primary winding of said repeating coil, a primary impulse responsive relay connected in circuit with the secondary winding of said repeating coil at said receiving station and so polarized as to be responsive only to the break impulses set up by said transmitting means, a secondary impulse responsive relay controlled by said primary impulse responsive relay, and a rectifying means connected in parallel with the winding of said latter relay and so poled as to render said relay slow to release.

35 3. In an impulse correcting system, means for transmitting short impulses of current, a primary relay responsive to said impulses, a quick operating secondary relay operable in response to each operation of said primary relay, impulse transmitting contacts controlled by said secondary relay and a rectifier connected in parallel with the winding of said secondary relay so poled as to retard the release of said secondary relay following each release of said primary relay whereby impulses of predetermined duration are retransmitted by said secondary relay.

40 4. In a signaling system, a transmitting station, a repeating station and a receiving station, a line extending between said transmitting station and said repeating station and having a first repeating coil therein, a line extending between said repeating station and said receiving station and having a second repeating coil therein, means at said transmitting station for transmitting impulses of direct current to the primary winding

45 of said first repeating coil, an impulse responsive relay at said repeating station connected to the secondary winding of said first repeating coil and so polarized as to be responsive only to the break impulses set up in said first repeating coil by said transmitting means, means controlled by said impulse responsive relay to transmit impulses of direct current to the primary winding of said second repeating coil and an impulse responsive relay at said receiving station connected to the secondary winding of said second repeating coil and so polarized as to be responsive only to the break impulses set up in the second repeating coil.

50 5. In a signaling system, a transmitting station, a repeating station, and a receiving station, a line extending between said transmitting station and said repeating station and having a first repeating coil therein, a line extending between said repeating station and said receiving station and having a second repeating coil therein, means at said transmitting station for transmitting impulses of direct current to the primary winding of said first repeating coil, a primary impulse responsive relay connected in series with a rectifier in circuit with the secondary winding of said first repeating coil at said repeating station, said latter relay being so polarized by said rectifier as to be responsive only to the break impulses set up in said first repeating coil by said transmitting means, a secondary impulse responsive relay controlled by said primary relay to transmit impulses of direct current to the primary winding of said second repeating coil, and an impulse responsive relay connected in series with a rectifier in circuit with the secondary winding of said second repeating coil at said receiving station, said latter relay being so polarized by said rectifier as to be responsive only to the break impulses set up in said second repeating coil by said secondary impulse relay.

55 6. In a signaling means, a transmitting station, a repeating station, and a receiving station, a line extending between said transmitting station and said repeating station and having a repeating coil therein, a line extending between said repeating station and said receiving station and having a repeating coil therein, means at said transmitting station for transmitting an impulse of pulsatory current through the primary winding of said first repeating coil, a first impulse responsive relay at said repeating station connected to the secondary winding of said first repeating coil and so polarized as to be steadily responsive to said current, a slow-to-release relay arranged to release upon the continued operation of said impulse responsive relay and while released to transmit an impulse of pulsatory current to the primary winding of said second repeating coil, a second impulse responsive relay at said receiving station connected to the secondary winding of said second repeating coil and so polarized as to be steadily responsive to said current, a slow-to-release relay arranged to release upon the continued operation of said second impulse relay, and a signal controlled by the release of said last relay.

60 7. In a signaling means, a transmitting station, a repeating station, and a receiving station, a line extending between said transmitting station and said repeating station and having a repeating coil therein, a line extending between said repeating station and said receiving station, and having a repeating coil therein, means at said

- transmitting station for transmitting an impulse of alternating current through the primary winding of said first repeating coil, a first impulse responsive relay at said repeating station connected to the secondary winding of said first repeating coil and so polarized as to be steadily responsive to said current, a slow-to-release relay arranged to release upon the continued operation of said impulse responsive relay and while 5 released to transmit an impulse of alternating current to the primary winding of said repeating

coil, a second impulse responsive relay at said receiving station connected to the secondary winding of said second repeating coil and so polarized as to be steadily responsive to said current, a slow-to-release relay arranged to release upon the continued operation of said second impulse relay and a signal controlled by the release of said last relay. 5
